UNITED STATES PATENT OFFICE.

CHESTER A. BACON, OF AUBURN, NEW YORK, ASSIGNOR TO BOWEN PRODUCTS CORPORATION, OF AUBURN, NEW YORK, A CORPORATION OF NEW YORK.

LUBRICATING DEVICE.

1,386,860.

Specification of Letters Patent. Patented Jan. 25, 1921.

Application filed April 19, 1920. Serial No. 374,924.

To all whom it may concern:

Be it known that I, CHESTER A. BACON, a citizen of the United States, and a resident of Auburn, in the county of Cayuga and State of New York, have invented certain new and useful Improvements in Lubricating Devices, of which the following is a specification.

This invention relates to improvements in lubricating devices and more particularly to the construction of a device of the character described, embodying the general features and functions of the ordinary type of compression grease cup, together with novel features of construction calculated to overcome certain disadvantages heretofore found to be present in the devices now in use.

Among the objects of my invention is to provide a lubricant device that is convenient of manipulation, particularly as regards the removal of the cap for the purpose of replenishing the lubricant. Broadly, this is accomplished by replacing the usual form of screw-threaded cap by an adaptation of the bayonet joint together with a simple and novel form of tension means designed to maintain the cap in place on the receptacle.

The features embodying my invention are hereinafter fully set forth and in connection with the accompanying drawings, wherein—

Figure 1 is a view of the device in elevation,

Fig. 2 is a view in vertical section of the device,

Fig. 3 is a view in vertical section of the cap and plunger removed from the receptacle of the device, and taken on line 3—3 of Fig. 4, and

Fig. 4 is a detailed view in section taken on line 4—4 of Fig. 2.

The form of lubricating device embodying the features of my invention consists of a receptacle 1 or body member consisting of a cylindric metal shell provided at one end with a threaded nipple 2 having a comparatively small discharge orifice 3, said nipple being provided with screw threads and adapted to be attached in the usual manner to the part or mechanism to be lubricated.

50 A cap or closure 4 fits over the open end of the receptacle, said cap being provided with an annular flange 5 adapted to engage and surround the upper margin of the receptacle.

Referring more in detail to the means employed for detachably connecting the cap

to the receptacle, the same involves the use of the so-called bayonet form of joint which in this instance comprises a plurality of detents 6 having the form of pins which are inserted inwardly through the flange 5 of the cap at diametrically opposed points, the inner ends of said pins projecting a short distance inwardly from the inner surface of said flange. Formed in the marginal portion of the receptacle are provided a corresponding number of notches 7, the same comprising a short entrance portion at right angles to the edge of the receptacle and an end portion at right angles thereto terminating in a slightly enlarged end portion as is clearly shown in Fig. 1. At the center of the cap is provided an opening in which is inserted a bushing 8 which forms a part adapted to retain a member hereinafter to be described, and in addition acts as a connection for a tension member, which will now be described. As clearly shown in Figs. 3 and 4, there is mounted adjacent to the upper wall of the cap and within the same a spring or tension member 9 comprising a central portion having an opening through which extends the bushing 8, the latter being provided with an outwardly spread shoulder which acts to retain the tension member rigidly in place and fixed to the cap 4. The tension member further consists of a plurality of radially extending spring fingers 10 which terminate adjacent to the inner surface of the flange 5 of said cap, said spring fingers of the tension member being adapted to engage the upper edge of the receptacle when said cap is applied to the receptacle in the act of detachably connecting the same thereto.

The function of the tension member and the method of connecting the cap to the receptacle will be understood from the following: The cap is first fitted over the end of the receptacle and rotated until the detents 6 enter the locking notches 7 and by applying a slight pressure and simultaneously rotating the cap in a clockwise direction, the detents come to rest in the enlarged ends of the locking notches, as is clearly shown in Fig. 1, said enlarged end portion in itself forming an additional locking means inasmuch as it is slightly offset in the direction of the edge of the receptacle.

Obviously, the spring fingers being fixed to the cap exert a pressure upon the recep-

tacle in the manner to force said members apart and thus apply the necessary pressure to maintain the parts in secure locking engagement.

5 In addition to the parts already described the device further comprises a plunger consisting of a plunger head 11 having a diameter substantially equal to that of the internal diameter of the receptacle, said head being provided with a packing ring 12 of any suitable material. Rigidly connected to the head 11 is a stem 13 provided throughout its length with screw threads, said stem passing through and engaging the bushing 8 located at the central portion of the cap 4. At the outer end of the stem and located on the exterior of the receptacle is a handle 14 adapted to be grasped by the fingers in operating or manipulating the plunger. 10 Within the interior of the receptacle and filling the space between the discharge orifice 3 and the plunger head 11 is a quantity of absorbent material 15 of any suitable variety, such as cotton waste, wicking, or the like.

15 The purpose of the wicking and the function of the plunger will now be described. A quantity of oil is poured or otherwise introduced into the receptacle by removing the cap together with the plunger, the quantity of oil thus fed to the receptacle being sufficient to completely saturate the mass of absorbent material 15. The cap is then applied to the receptacle and connected thereto in the manner heretofore set forth, the plunger being first screwed outwardly to the limit of its movement in order that it will exert very little or no pressure upon the mass of absorbent material. In order to force the oil from the receptacle and through the discharge orifice 3 it is only necessary to screw down the plunger by means of the handle 14, the extent of movement of the plunger being determined by the quantity of oil desired. Obviously, by this arrangement the oil will be held in saturation by the mass of absorbent material and will not flow from the receptacle through the discharge orifice so long as the plunger is not operated to compress the mass of absorbent material. 20 Thus it is possible to maintain oil at all times within the receptacle, which oil will not en-

ter the parts to be lubricated unless so desired by the operator. Furthermore the quantity of oil which may be fed from the receptacle can be accurately controlled by the operation of the plunger so that the necessary amount of lubricant can be introduced into the parts by a known movement of the plunger. For instance, it may be known to the operator that exactly four drops of lubricant will be discharged by rotating the plunger stem through a quarter of a turn and in this manner the operator will know at all times just how much lubricant is being used and thus enable him to properly lubricate the parts.

25 By employing the specific form of locking device hereinbefore described the operation of applying the cap becomes exceedingly simple, it being only necessary to rotate the cap until locking engagement is effected, the tension of the spring upon the parts assuring the connection between the parts and prevents the loss of the cap. Furthermore, by this type of locking means the use of the usual screw threaded connection between the cap and the receptacle is eliminated, this connection being ordinarily the source of considerable inconvenience inasmuch as it is often difficult to properly engage the threads, particularly where the lubricating device is located in a position inconvenient of access.

30 The features embodying my invention are further set forth in the appended claim.

I claim as my invention:

35 A lubricating device comprising an open receptacle, a cap fitting over the opening of said receptacle and detachably connected thereto, said cap being provided with a centrally located opening, a bushing fitted in said opening through the medium of an annular groove interfitting with the edge of said opening, a flat tension spring fixed to 40 said cap by means of a central aperture engaging the groove of said bushing, and a stem extending through said bushing and having screw threaded engagement therewith.

45 In witness whereof, I hereunto subscribe my name this 29 day of March, A. D. 1920.

50 CHESTER A. BACON.
